UNITED STATES PATENT OFFICE.

AUGIE L. HANSEN, OF EVANSTON, ILLINOIS.

ACETYLENE-LAMP.

1,310,529.

Specification of Letters Patent.

Patented July 22, 1919.

Application filed May 6, 1918. Serial No. 232,774.

To all whom it may concern:

Be it known that I, AUGIE L. HANSEN, a citizen of the United States, residing at Evanston, in the county of Cook, State of Illinois, and having a post-office address at No. 2108 Lincoln street, Evanston, Illinois, have invented certain new and useful Improvements in Acetylene-Lamps, of which the following is a full, clear, and exact description.

My invention relates to various new and useful Improvements in acetylene lamps and the improvements have been particularly designed for use in connection with small miners' cap lamps. In Letters Patent of the United States No. 1,162,915, dated December 7, 1915, I described certain improvements in acetylene lamps and in the development of that lamp I found that certain improvements therein are desirable. In my patented lamp I dispensed entirely with the usual centrally arranged water tube and instead I made use of a short water tube leading from the water reservoir to the threaded connection between the carbid chamber and the upper part of the lamp, whereby the water before it reached the carbid followed the screw-threads upwardly so as to flow over the edge of the neck of the carbid chamber and thus enter the carbid chamber as a film or thin stream flowing down upon the inside of the carbid chamber to thus reach the carbid. With my patented lamp, notwithstanding the small hydrostatic head, a comparatively high gas pressure was permitted to develop in the carbid chamber because in order that the water might be forced back into the water reservoir, it was necessary for it to be backed up through the very thin passage formed between the threads on the neck of the carbid chamber and the depending flange respectively. In the construction and operation of the patented lamp I discovered opportunity for improvement. In the first place, I found that there was some danger, when the lamp was in use, of water being shaken off of the wall of the carbid chamber when the lamp was suddenly jolted by the miner so that the water in comparatively large drops would be thrown out into the carbid, resulting in over-generation of gas and in an objectionable variation of the flame. I also discovered that the best results are not secured when the water is introduced into the carbid from the top

downwardly, as suggested in my patent, because when this is done, an undesirably large amount of water is evaporated within the carbid chamber and condenses on the walls thereof, from which it again flows into the carbid, so that the operation of evaporation and condensation continues to take place. With any carbid lamp there is a certain amount of evaporation and condensation, but when water is fed to carbid from the top downward, the condensation is greater. Too much water in the carbid chamber also objectionably saturates the usual felt filter and interferes with the proper filtering of the gas to the burner. The amount of water evaporated in the carbid chamber should not be in excess of the absorbing capacity of the usual felt filter pad used in these lamps.

To improve the lamp in these respects, I have designed my present lamp with a sleeve or apron located on the inside of the carbid chamber and forming a thin channel through which the water may pass so as to reach the carbid well below its top surface. This sleeve or apron carries the threaded neck by which the carbid chamber is securely screwed to the top of the lamp. The packing between the carbid chamber and the top of the lamp is a rubber gasket interposed on the outside between the carbid chamber and an inclined flange at the bottom of the lamp top. By locating the packing at this point no possible leakage of gas can take place. In my improved lamp, the water from the water reservoir is introduced into the space formed between the carbid chamber and said sleeve or apron near the very top thereof. Through this space the water flows downward, apparently as a thin stream or film, until it reaches the carbid and upon the generation of gas the pressure of the latter will check the flow until the gas pressure drops when more water is needed. Thus the flow of water from the reservoir takes place intermittently, being controlled by the gas pressure.

It is important, of course, that there should not be an objectionable choking of the water space between the sleeve or apron and carbid chamber. Ordinarily this water space presents such a great area, notwithstanding the close proximity of its opposed walls, that even when very considerably clogged, sufficient opportunity is offered for

the feed of water to the carbid, since only a minute quantity of water is necessary to operate these lamps. In time, however, there might be complete clogging of the water space between the sleeve or apron and the carbid chamber, and therefore to prevent this, I arrange the sleeve or apron and carbid chamber so that there may be a relative movement of these parts whenever the carbid chamber is engaged or disengaged from the top and, if desired, this relative movement may be effected at any time during the operation of the lamp by slightly twisting the carbid chamber back and forth. In other words, the sleeve or apron and carbid chamber are so associated that the latter may be given a partial turn backward or forward without disturbing the engagement of the threaded connection between the neck of the sleeve or apron and the top, and, of course, the gas seal is not disturbed because in this movement there is no relative separation of the carbid chamber with respect to the top. To this end, I provide the sleeve or apron and carbid chamber with interlocking abutments which will come into engagement when the carbid chamber has been twisted to a predetermined extent. Afterward the carbid chamber and sleeve or apron will move together as a whole to permit the threaded connection to be made or separated as the case may be.

In order that my invention may be better understood, attention is directed to the accompanying drawing, forming a part of this specification in which:

Fig. 1 is a full-sized vertical sectional view through a miner's cap-lamp, showing my present improvements therein.

Fig. 2, a corresponding view on an enlarged scale, for the purpose of more clearly illustrating the lower part of the water tube with its controlling valve.

Fig. 3, a cross-section on the line 3—3 of Fig. 1, showing particularly the locking abutments.

Fig. 4, a plan view of the threaded sleeve or apron.

Fig. 5, a side view of the same, and Fig. 6, a detail view on the same scale as Fig. 2, showing the arrangement of the lower end of the water tube.

In the above views, corresponding parts are indicated by the same reference numbers.

The top 1, of the lamp contains the water-reservoir 2, having the vented filling cap 3, and in the front of the top is the reflector 4, with burner tip 5 to which leads the tube 6, passing through the bottom wall of the water reservoir and with its lower end protected by a felt filter pad 7, removably held in place by a sheet metal clip 8, all as well-known in the art. The top 1 is provided with the usual flange 9, between which and

the inclined shoulder of the carbid chamber 10 is interposed a packing 11, generally a rubber gasket.

With acetylene lamps as heretofore made, the carbid chamber has been directly attached to the top 1, usually by a screw-threaded connection. With my improved acetylene lamp, I make use of a sleeve or apron 12, having a threaded neck 13 which engages with the usual screw threads 14 on the lamp top. The sleeve or apron fits the inside of the carbid chamber quite snugly, the space separating the two being somewhat exaggerated in the drawing for the purposes of clearness. In practice this water space is sufficiently contracted to permit water to flow down the same as a thin sheet or film with a retarded or substantially capillary effect as distinguished from a free unimpeded flow. In this way I am able to reduce the rate of flow sufficiently so that when the gas pressure drops, the desired minute quantity of water will enter the carbid. In the operation of these lamps, it is important that when a feed of the water takes place, it shall be a very small quantity, since if the water is allowed to enter the carbid chamber in a relatively large amount, there will be objectionably great fluctuations in the gas pressure and corresponding variations in the length of the flame. Furthermore, by providing a capillary space between the sleeve or apron and the carbid chamber, a substantial retardation is offered to the return movement of the water in addition to the added length of the hydrostatic head as compared to the lamp of my patent referred to. Thus it becomes possible to burn the lamp under relatively high pressure since, after the feed has been arrested, the gas pressure may increase to the point where the gas has forced the water upwardly and escapes through the water reservoir.

In order to prevent the closing of the water space between the shoulder of the sleeve or apron and the flange of the carbid chamber when these parts are tightly pressed together in screwing the carbid chamber in place, I form the sleeve or apron on its shoulder with a number of shallow ribs 15, between which are channels 16 through which the water may pass, as will be obvious. I also illustrate the sleeve 12 as being provided with two diametric ribs 17, fitting the inner wall of the carbid chamber and I also show the carbid chamber as formed with two diametric ribs, 18, projecting inwardly and fitting the sleeve or apron. The ribs 17 are formed by stamping the metal of the sleeve or apron inward to form two panels 19 in which the ribs 18 extend, although, of course, it will be understood that the ribs 17 may be pressed outwardly beyond the plane of the sleeve or apron. By means of the ribs 17 and 18 the sleeve or apron will be cen-

tered with respect to the carbid chamber so as to preserve the concentricity of the water space between the two. The principal function of these ribs 17 and 18 is to limit 5 the twisting movement of the carbid chamber with respect to the sleeve or apron. When the carbid chamber is to be removed, it is turned until the ribs 18 engage the ribs 17, whereupon the sleeve or apron will be 10 unscrewed from the top 1. In applying the carbid chamber in position, the reverse operation takes place, the carbid chamber turning with respect to the sleeve or apron until the ribs or abutments engage, whereupon 15 the threaded neck of the sleeve or apron will be forced into engagement with threads 14. At any time during the operation of the lamp, the carbid chamber may be given a short twisting movement back and forth 20 without disturbing the screw-threaded connection with the lamp top. By thus providing a lamp in which the carbid chamber, whenever it is placed in position or removed, will be moved relatively to the sleeve or 25 apron, I keep the water passage entirely clear and open and prevent any possibility of clogging by carbid particles or by any sediment which may be contained in the water. The cleaning of the water channel 30 therefore takes place automatically whenever a new charge of carbid is introduced, although, if desired, should the flame become unsteady, due to clogging, the water space may be cleaned as described during the 35 operation of the lamp. In assembling the sleeve or apron within the carbid chamber, it is introduced from the bottom upward and to permit it to pass the ribs 18 it is formed with two notches or nicks 20 thus 40 allowing the ribs 18 to enter the depressed panels 19 between the ribs 17. After the sleeve or apron has thus been inserted in place, a bead 21 is stamped or otherwise formed in the carbid chamber to act as a 45 stop to prevent the sleeve or apron from dropping down. Finally, in the assembling operation, the bottom 22 of the carbid chamber is soldered or otherwise secured in place.

Water from the reservoir 2 flows down a 50 channel 23 into the space between the sleeve or apron 12 and the carbid chamber. Preferably the metal is cut away as at 24 (Fig. 6) around the discharge of the water channel 23 so as to permit unimpeded water 55 flow at this point and reduce the danger of clogging and at the same time allowing any accumulated sediment to be easily removed. The upper end of the water channel 23 constitutes a valve seat with which 60 operates a valve 25 operated by a handle 26. This valve is of any suitable type; it performs the usual function of regulating the rate of flow of the water. Extending downwardly through the valve tube is the usual 65 wire 27 projecting through the water chan-

nel 23 and serving not only to restrict and retard the flow of water, but also keeping the water channel clean at all times. Water from the reservoir enters the valve chamber through the slot 28 in the usual way. 70

Having now described my invention, what I claim as new therein and desire to secure by Letters Patent, is as follows:

1. In an acetylene lamp, the combination with a carbid chamber and a water reservoir, of a sleeve or apron in the carbid chamber and engaging the same and forming an annular contracted water passage extending well within the carbid chamber, a connection between said sleeve or apron and the water reservoir by which the carbid chamber and water reservoir will be securely held together and a water conduit leading from the reservoir to said contracted annular passage, substantially as and for the 85 purposes set forth.

2. In an acetylene lamp, the combination with a carbid chamber and a water reservoir, of a sleeve or apron in the carbid chamber and engaging the same and forming an annular contracted water passage extending well within the carbid chamber, a screw threaded connection between said sleeve or apron and reservoir by which the carbid chamber and water reservoir will be 90 securely held together and a water conduit leading from the reservoir to said contracted annular passage, substantially as and for the 95 purposes set forth.

3. In an acetylene lamp, the combination with a carbid chamber and a water reservoir, of a sleeve or apron in the carbid chamber and engaging the same and forming an annular contracted water passage extending well within the carbid chamber, 100 a connection between said sleeve or apron and water reservoir by which the carbid chamber and water reservoir will be securely held together, a water conduit leading from the water reservoir to said contracted annular passage, and the gas seal between the carbid chamber and the reservoir outside of said sleeve or apron, 105 substantially as and for the purposes set forth.

4. In an acetylene lamp, the combination with a carbid chamber and a water reservoir, of a sleeve or apron in the carbid chamber and engaging the same and forming an annular contracted water passage extending well within the carbid chamber, 110 a screw threaded connection between said sleeve or apron and water reservoir by which the carbid chamber and water reservoir will be securely held together, a water conduit leading from the water reservoir to 115 said contracted annular passage, and a gas seal between the carbid chamber and the reservoir outside of said sleeve or apron, 120 substantially as and for the purposes set forth.

5. In an acetylene lamp, the combination with a carbid chamber and a water reservoir, of a sleeve or apron on the inside of the carbid chamber and engaging the same and forming a contracted annular water channel, a connection between the sleeve or apron and the water reservoir, a water conduit leading from the water reservoir to said annular passage and interlocking abutments on the carbid chamber and sleeve respectively, whereby there may be a relative movement of the carbid chamber and sleeve until said abutments engage and thereafter the carbid chamber and sleeve will move together, substantially as and for the purposes set forth.
6. In an acetylene lamp, the combination of the carbid chamber and a water reservoir of a sleeve or apron on the inside of and engaging the carbid chamber and between which and the carbid chamber a con-

tracted water passage is formed, said carbid chamber and sleeve being movable relatively and circumferentially, substantially as and for the purposes set forth.

25

7. In an acetylene lamp, the combination with the carbid chamber and a water reservoir, of a sleeve or apron on the inside of and engaging the carbid chamber and between which and the carbid chamber a contracted water passage is formed and a connection between said sleeve or apron and the water reservoir, whereby the carbid chamber and said water reservoir may be secured tightly together, substantially as set forth.

35

This specification signed and witnessed this 24th day of April, 1918.
